CLAIM

The ornamental design for the heart rate monitor as shown and described.

DESCRIPTION

FIG. 1 is a front, top perspective view of a heart rate monitor showing our new design;
FIG. 2 is a rear, bottom perspective view thereof;
FIG. 3 is a top view thereof;
FIG. 4 is a bottom view thereof;
FIG. 5 is a left side view thereof;
FIG. 6 is a right side view thereof;
FIG. 7 is a rear view thereof; and
FIG. 8 is a front view thereof;
FIG. 9 is an enlarged view of FIG. 5;
FIG. 10 is an enlarged view of FIG. 6;
FIG. 11 is an enlarged view of a portion of FIG. 8; and,
FIG. 12 is an enlarged view of a portion of FIG. 9.
The dot-dash broken lines depict the boundaries of the claimed design and form no part thereof. The dash-dot broken lines depict portions of the heart rate monitor that form no part of the claimed design.

1 Claim, 6 Drawing Sheets
